UNITED STATES PATENT OFFICE.

WILLIAM H. BROWN, OF LOS ANGELES, CALIFORNIA, ASSIGNOR OF ONE-HALF TO
LUTHER G. BROWN, OF LOS ANGELES, CALIFORNIA.

TRUCK.

1,096,350.

Specification of Letters Patent.

Patented May 12, 1914.

Application filed December 24, 1912. Serial No. 738,457.

To all whom it may concern:

Be it known that I, WILLIAM H. BROWN, a citizen of the United States, residing at Los Angeles, in the county of Los Angeles 5 and State of California, have invented a certain new and useful Improvement in Trucks, of which the following is a specification.

My invention relates to a truck particularly for handling and transporting large 10 and bulky articles, especially large and heavy rolls of paper such as are used in newspaper and other publishing plants. In order that the nature and object of this invention may be fully understood, it may be 15 stated that the damage to such paper rolls, as a result of carelessly dumping them from the vehicles in which they are carried, is very large, inasmuch as the edges of the rolls become crushed and such crushed and crumpled portions of the paper must be cut off 20 because they will not pass through the press. Again, no small damage to the edges of the rolls is occasioned by the lips of the ordinary trucks which, when forced under the 25 paper edge, tear or render a good portion unfit for use.

Objects of this invention, therefore, are to provide a truck upon which the paper rolls may be deposited directly from the delivery wagons; in which the edges of the 30 rolls are always guarded, and by means of which the paper rolls may be set in upright position without using the edges of the same as pivots for this purpose. These and other 35 objects are accomplished by the truck represented in the accompanying drawing, in which,

Figure 1, is a side elevation, showing the truck embodying my invention, and a roll of 40 paper carried thereby. Fig. 2, is a side elevation, showing the platform of the truck in tilted position, and the operative position 45 of the lip for holding the paper roll on the platform, dotted lines indicating the position of the lip after the roll has been raised to vertical position, and Fig. 3, is a sectional elevation on lines *a—a*, Fig. 1.

The truck consists of a frame 1, supported 50 at its forward end by wheels 2, journaled on an axle 3, and at its rear end by legs 4. On a trunnion 5, mounted in suitable bearings 6, on the frame, is a platform or bed 7, which consists of a channel iron 8, and substantially V-shaped braces 9, to the ends 55 of which are fastened longitudinal support-

ing rods 10, which are arranged to give lateral support to a roll of paper. The ends 10', of these supporting rods are slightly curved downwardly and are designed to rest on the ground or floor when the bed is tilted 60 to the position shown in Fig. 2. Pivoted in and extending beyond the end of said channel iron 8, is a lip 11, having an elongated end 12, for the purpose of holding said lip in position for engagement by a roll 65 when the bed is tilted. The movement of a roll of paper on the supporting rods 10, is limited, as seen, by the lip 11, which is sufficiently large to prevent the weight of the roll from injuring the edges thereof. When 70 the roll is gradually lifted from the position shown in Fig. 2, the lip 11, will gradually remove from engagement with the edge of the roll, as this edge, following the curvature of the ends 10', of the supporting rods 10, 75 moves in the opposite direction from that of the said lip 11. At the time, therefore, that the lip has escaped from the edge of the roll, the roll will be in substantially vertical position, thus preventing injury to the edges 80 of the roll when it finally comes to rest. It will be obvious that where two or more rolls of paper of smaller length than a full roll are deposited on the truck platform, they may be set in upright position in exactly the 85 same manner as the large rolls.

What I claim, is:—

1. A truck for paper rolls and the like comprising a frame, a bed pivotally mounted on said frame and extending beyond the 90 end of the same, and a lip pivoted in and extending beyond the forward end of said bed to hold a roll of paper thereon when tilted, said lip automatically removing from the edge of the roll when said roll is raised to 95 vertical position.

2. A truck for paper rolls and the like, comprising a frame having a pair of wheels, a bed pivotally mounted on said frame and consisting of connected supporting rods and 100 a channel iron disposed between said rods, said rods having their ends slightly curved downwardly, and a lip pivoted in the forward end of and extending beyond said bed to hold a roll of paper on said bed when 105 tilted, said lip being arranged to automatically remove from the edge of said roll when said roll is raised to vertical position.

3. A truck for paper rolls and the like, comprising a frame having a pair of wheels, 110

and handles, a trunnion on said frame, a plurality of braces one of which is fastened to said trunnion, a channel iron carried centrally of said braces and forming a central support for said roll, a plurality of rods also carried by said braces and forming a lateral support for said roll, said rods having their ends curved downwardly, and a lip pivoted in and extending beyond the end of said channel iron to support the paper roll

in tilted position, and being arranged to automatically remove from engagement with said roll when said roll is raised to vertical position.

In testimony whereof I have set my hand 15
in the presence of two witnesses.

WILLIAM H. BROWN.
